(57) **CLAIM**

The ornamental design for toy toilet, as shown and described.

DESCRIPTION

FIG. 1 shows a front elevation view of the toy toilet.

FIG. 2 shows a rear elevation view thereof.

FIG. 3 shows a right side elevation view thereof, the opposite side being a mirror image thereof.

FIG. 4 shows a top plan view thereof.

FIG. 5 shows a bottom plan view thereof.

FIG. 6 shows a top and side perspective view thereof; and, FIG. 7 shows a bottom and reverse side perspective view thereof.

The broken lines shown in the figures are for the purpose of illustrating portions of the toy toilet and form no part of the claimed design.
